UNITED STATES PATENT OFFICE

2,659,393

ARRANGEMENT FOR THE FORMATION AND BEATING UP OF THE WEFTS IN CIRCULAR WEAVING LOOMS

Jean Dunod, Paris, France, assignor to Qualitex-Société Dunod & Cie, Paris, France, a corporation of France

Application July 26, 1951, Serial No. 238,675

Claims priority, application France July 27, 1950

2 Claims. (Cl. 139—13)

1

This invention relates to circular looms wherein several shuttles are driven, or rather entrained, by a non-positive drive, this being effected by substantially horizontal arms keyed on a vertical shaft. The invention is particularly but not exclusively concerned with looms of this kind wherein the shuttles are entrained by the attraction of electro-magnets mounted upon each of the revolving arms.

One object of the invention is to provide a shuttle particularly adapted for the non-positive mode of entrainment and at the same time adapted for facilitating the laying of the weft.

A second object is to provide a particularly advantageous magnetic means for the entrainment of the shuttles.

Yet another object is to provide an advantageous means for beating up the weft laid by the means aforesaid.

In the annexed drawings one practical means according to the invention is illustrated diagrammatically and by way of example, in which drawings:

Figure 1 is a perspective view of a shuttle and a bobbin therein,

Figure 2 is an axial section of the bobbin in Figure 1,

Figure 3 is a perspective view to a larger scale, showing the formation of the weft,

Figure 4 is a diagrammatic plan explanatory of the driving of the shuttles,

Figures 5 and 6 are diagrams explanatory of the effect of magnetic attraction and repulsion for the driving of the shuttles,

Figure 7 is an elevation of one half of a loom incorporating the present improvements,

Figure 8 is the other half of the loom in vertical section,

Figure 9 is a view of the beating-up mechanism in section on the line IX—IX of Figure 10,

Figure 10 is a plan corresponding with Figure 9,

Figure 11 is a view to a larger scale of a detail in Figure 9, this view being in section on the line XI—XI of Figure 12,

Figure 12 is a section, to the same scale, on the line XII—XII of Figure 11.

As will be seen from Figures 1 to 3, the bobbin 68 is mounted removably in a shuttle 72 which runs on the reed 108 and is guided by a side flange 108c against which bear rollers 108b of the shuttle. The latter has at its rear end a slender hollow point 71 for the passage of the weft thread. It will be seen in Figure 1 that the weft thread 69 wound on the bobbin 68 passes first through

5 a central tube 70 of the bobbin, then turns forwardly past the fixing ring 68, as shown in Figures 1 and 2. It then passes into the tailpiece 68d of the shuttle and is laid in the inverted bottom of the shed by the point 71. A clip 100 serves for fixing the bobbin in the shuttle 72.

Figure 3 shows how the weft-thread 69 is laid by the shuttle 72 in the shed opened by disposing alternate warp threads towards respective 10 sides of the reed 108. This is done by a shed-opening mechanism forming no part of the present invention but preferably of the type described in a concurrent patent application No. 238,674, filed July 26, 1951. This mechanism is represented diagrammatically by heddles 43 and 44 (Figures 3 and 8) actuating the threads 26. It is necessary, in order to pass the thread 69 through the central tube 70 (Figure 2) and returning it towards the said tail-piece, to use the body of the bobbin for guidance. In fact, the changing of the bobbin would be made very difficult if such guidance were provided by a device fixedly mounted in the shuttle.

Figure 4 shows the means for entraining the 25 shuttle, said means comprising devices on the shuttle and cooperative devices carried by revolving arms, and these will be described later.

When the weft is laid, the shed is closed after the passage of the shuttle whereupon the warp threads are all disposed along the inner edge 108a of the reed 108 as seen to the right hand in Figure 3. The tailpiece 71 of the shuttle guiding the weft thread 69 must therefore be directed away from this side. It is to be noted that the weft is laid when the warp threads are tensioned normally, so that risk of breakage of thread is relatively small. To the left hand in Figure 3, the shed is seen to be open before the passage of the shuttle and to the right hand, the shed is seen to be re-closing after the passage of the body 72 of the shuttle and during the passage of its tailpiece 71.

The means for entraining the shuttles is illustrated diagrammatically in Figure 4. This means must permit at all times of leaving a free space between the shuttle and the driving means such space being occupied by the warp threads. At the same time, the said means must be sufficiently effective for ensuring that there is no risk of loss of driving connection between a shuttle and its driving means particularly when the driving effort demanded is a maximum as when starting or stopping the loom.

This problem is solved by the invention in the 55 following manner: On the central shaft 67 of

3

the loom are keyed arms 13 in number equal to the number of shuttles 12 (three in the example illustrated) these arms being regularly spaced. Each arm carries at its extremity, opposite a respective shuttle, two magnet coils 14 and 15 (Figures 4 to 6 and 8).

To cooperate with these coils, the shuttle is fitted with armatures 16 and 17, the armatures 17 being conductive but not magnetic (for example solid aluminium) whilst the others 16 are magnetic and relatively non-conductive (for example of laminated iron). The armatures 17, in fact, are suitable for the development of Foucault currents.

The coils 14 and 15 are traversed by electric impulses of very short duration and of high tension and intensity supplied by a generator 81 (Figure 4) to a fixed brush 18 rubbing on a slip ring 19 connected with the circuits 80 of the coils 14 and 15. The second pole of the generator 81 is similarly connected to a second slip ring 19a. The generator 81 is of known type used particularly in radar installations and its function is to charge a condenser under a tension of the order of 2,000 volts, the condenser discharging into a solenoid. The impulses produce a purely magnetic attraction on the magnetic armature 16 and a repulsion on the non-magnetic armature 17 by induction of Foucault currents therein.

Each shuttle 12 is thus both simultaneously attracted and repelled. By a suitable disposition of coils and armatures as hereinafter indicated, the shuttle is not submitted to any radial effort but only to resultant tangential forces of attraction and repulsion, a tractive effort being produced so that the shuttle is entrained around its run-way which is, in general, constituted by the reed 108.

On the other hand, the system producing two tangential resultants directly opposed to one another, the shuttle finds itself with a sort of elastic connection with the extremity of a corresponding driving arm. Figures 5 and 6 illustrate the mode of operation of this magnetic arrangement.

In the position of rest (Figure 5) the magnetic centres 15a and 15b of the magnet coils 15 are disposed symmetrically in regard to the magnetic centres 11a and 11b of the non-magnetic masses 11 and 16a of the magnetic mass 16. The forces operating are repulsion forces R_1 and R_2 , which can be split into radial components r_1 and r_2 and tangential components V_1 and V_2 , and attraction forces A_1 and A_2 which can be split similarly into a_1 and a_2 and b_1 and b_2 .

At this moment, if the sum of the forces be represented by Σ , then:

$$\Sigma(V_1 V_2 + b_1 b_2) = 0$$

By a suitable choice of respective positions for the magnetic centres, it is also possible to obtain:

$$\Sigma(r_1 r_2 + a_1 a_2) = 0$$

In the operating position, Figure 6, the magnet coils are displaced in relation to the parts entrained in the direction of driving, since the inertia of the shuttle causes the latter to lag behind the revolving arm which turns in the direction of the arrow F.

The relation between the distances of the magnetic centres gives:

$$\Sigma(V'_1 V'_2 + b'_1 b'_2) = 0 = W \text{ (resultant force)}$$

whilst preserving:

$$\Sigma(r'_1 r'_2 + a'_1 a'_2) = 0$$

4

It is understood that matters are so arranged that the direction of the resultant force W is the same as that of the movement of the arm 13, that is to say of the arrow F, Figure 6.

It results that the shuttle is entrained in the same direction as the arm 13.

The arrangement for beating up the wefts is illustrated in detail in Figures 7 to 12 and Figures 7 and 8 show the relative position of this arrangement in the loom. This mechanism operates, after the passage of the shuttle, to beat up the weft thread into the inverted bottom of the shed. The function therefore is the same as that of the beating up reed in a rectilinear loom.

The woven fabric 192, above the level where the weft 69 is laid, passes between two concentric rails 103a and 103b. The inner rail 103a is fixed to a frame part 184 supported upon the shaft 67 through the intermediary of ball bearings 185 and the outer rail 103b is supported by brackets 183 on columns 182 which support the upper frame of the lever (Figures 7 and 8).

The weft-beating mechanism is situated immediately beneath the rails 103a, 103b. It is in the form of a multiple reed composed of independent elements 180 having tails or prolongations 180a directed downwardly (Figures 9 and 11) upon which is laid the weft thread 69, Figure 11. These elements 180 are mounted on the inner rail 103 in openings 174 (Fig. 12) in a coronet or ring 175 and are pivotal about axles 176. The said elements 180 are under the influence of spring rings 177 which constantly tend to move them into the position shown in full lines in Figure 9. It is in this position that they receive the weft thread 69 laid by the tail piece 11 of the shuttle. The beating up of the weft is effected as follows: On the central shaft 67 are keyed six arms (Figure 10) three of which marked 13, already mentioned, carry the magnet coils 14 and 15 and the other three (of which only two appear partially or wholly in Fig. 10), marked 178 carry horizontal wheels 179 adapted for having rolling action against the tails 180a of the elements 180. These wheels 179 are at such a distance from the axis of the shaft 67, that they press these tails against the action of the springs 177 and cause the elements 180 to oscillate about the pivots 176. In this movement, they raise the weft thread 69 and bring it into the inverted bottom of the shed opening so that they come into the position shown in dotted lines in Figure 11.

Naturally, the arms carrying the wheels 179 are keyed angularly in relation to the cams 39, 40 which control the to-and-fro movements of the heddles 43, 44, Figure 8, in such manner that the beating up of the weft 69 is effected at the time that the warp threads are crossed.

It is to be understood that although there has been described above a particular mode of entrainment of the shuttles by electro-magnetic attraction and repulsion, the invention comprises generally the combination with a non-positive drive or entrainment of the shuttles by revolving arms carried by a vertical shaft, of an arrangement for beating up the weft threads in the manner set forth.

I claim:

1. Arrangement for the formation and beating up of the wefts in a circular weaving loom in which the shuttles are entrained in a non-positive manner by means of arms revolving solidly with a central vertical shaft, comprising in combination bobbins each comprising a central bore

through which the weft thread is passed from back to front and a fixing ring at the front for engaging with the shuttle, shuttles each carrying at the front a fixing clip for engaging with a bobbin and at the rear a tail terminated by a fine point, means on each shuttle for ensuring the entrainment thereof in cooperation with corresponding means carried by corresponding revolving arms, concentric horizontal rails between which the woven fabric is passed, spring-influenced vertically oscillating blades disposed radially beneath the said rails and having at their inner ends tail-like prolongations, arms turning solidly with the said vertical shaft of the loom and distinct from the arms for entrainment of the shuttles, and horizontal wheels carried by these arms and rolling against the tail-like projections of the blades.

2. Arrangement as claimed in claim 1, wherein the entrainment means on each shuttle comprises 20

an armature conductive but not magnetic and an armature magnetic but not conductive, and corresponding means on each arm comprising two coils, a source of electric impulses of high tension and high intensity but of short duration, and electric circuits comprising fixed brushes and slip rings connecting the source of impulses to the two coils mounted upon each revolving arm.

JEAN DUNOD.
